UNITED STATES PATENT OFFICE.

ROBERT EMIL WALThER, OF WERDAU, GERMANY.

INCANDESCENT BURNER FOR LIQUID HYDROCARBONS.

No. 855,824.

Specification of Letters Patent.

Patented June 4, 1907.

Application filed January 22, 1907. Serial No. 353,428.

To all whom it may concern:

Be it known that I, ROBERT EMIL WALThER, a subject of the King of Saxony, and a resident of Schulstrasse 5, Werdau, Kingdom 5 of Saxony, German Empire, have invented a new and useful Improvement in Incandescent Burners for Liquid Hydrocarbons, of which the following is a specification.

This invention relates to improvements in 10 atmospheric burners for liquid combustibles for lighting and heating purposes.

According to my invention the burner is provided with a wick tube head in the form of a hollow open ring of metal preferably 15 metal of small heat conducting capacity, closed and sloped at the top. Fresh air continually entering and passing through the hollow space within the ring takes up the greater part of the heat which is imparted to 20 it by the flame and rapidly conducts it away to the surrounding air so that transmission of the heat to the wick tube is prevented, the combustion of the wick at the wick tube insured over the entire exposed outside and 25 heating of the wick tube and distortion of the burner prevented. A hollow ring of this kind can be very easily made in comparison with solid rings made for example from steatite or the like and in comparison therewith is very 30 durable and very cheap while being just as useful and efficient.

Onto the hollow ring is drawn a smooth 35 perforated or a corrugated ring ending with its top edge in the same horizontal plane as the top edge of the said hollow ring and being prevented from slipping off by a projecting flange on the hollow ring and in the corrugations of which are provided air entrance openings, for the purpose of conducting air in 40 definite quantities and in the form of jets to the sloped off or shouldered down upper edge of the hollow ring and thereby insure an always uniform burning of the flame.

On the accompanying drawing Figure 1 is 45 a vertical section of the atmospheric burner, Fig. 2 is a plan view and a partial horizontal section of the atmospheric burner.

a is a hollow open ring of metal closed and sloped at the top, forming the wicktube head. 50 b is the wick externally surrounded by the wick tube c, onto which the wick tube head a is fixed in such a manner that fresh air will continually enter and pass through the hol-

low space within the ring a. Therefore the latter will rapidly conduct the greater part of 55 the heat which is imparted to it by the flame away to the surrounding air so that a transmission of the heat to the wick tube is prevented, the combustion of the wick at the wick tube insured over the entire exposed 60 outside and heating of the wick tube and distortion of the burner prevented.

d is a corrugated ring drawn onto the hollow ring a and e is a projecting flange on the hollow ring, which prevents the corrugated 65 ring d from slipping off. Within the corrugations of the latter are provided air entrance openings f, for the purpose of conducting air in definite quantities and in the form of jets to the sloped off or shouldered down 70 upper edge of the hollow ring and thereby insure an always uniform burning of the flame.

The construction hereinbefore described is 75 simple as it requires but few parts to form an effective and very economic burner.

What I claim is:

1. In an atmospheric burner for liquid combustibles for lighting and heating purposes the combination with a wick, of a wick 80 tube externally surrounding the wick of a hollow open ring of metal closed and sloped at the top and provided on the wick tube thus forming a wick tube head of a second ring drawn onto the hollow ring and ending 85 with its top edge in the same horizontal plane as the top edge of said hollow ring of air entrance openings in said second ring for conducting air in definite quantities to the sloped off upper edge of the hollow ring and 90 of means for preventing the second ring from slipping off the hollow ring, substantially as described and specified.

2. In an atmospheric burner for liquid combustibles for lighting and heating purposes the combination with a wick, of a wick 95 tube externally surrounding the wick of a hollow open ring of metal closed and sloped at the top and provided on the wick tube thus forming a wick tube head, of a corrugated ring drawn onto the hollow ring and ending with its top edge in the same horizontal plane as the top edge of said hollow ring of air entrance openings provided within the corrugations of said ring for conducting air in 100 definite quantities and in the form of jets to 105

the sloped off upper edge of the hollow ring, and of a projecting flange provided on the hollow ring and preventing the corrugated ring from slipping off the same, substantially as described and specified.

In testimony, that I claim the foregoing as my invention, I have signed my name in pres-

ence of two witnesses, this tenth day of January, 1907.

ROBERT EMIL WALThER.
